Patented Oct. 5, 1920.

Inventor:
Alphonse Matera,
By his Attorney
Geo. M. Nieth

UNITED STATES PATENT OFFICE.

ALPHONSE MATERA, OF NEW YORK, N. Y.

DESIGN FOR A BUST-COVER.

56,370.

Specification for Design.

Patented Oct. 5, 1920.

Application filed May 13, 1920. Serial No. 381,210. Term of patent 7 years.

To all whom it may concern:

Be it known that I, ALPHONSE MATERA, a citizen of the United States, residing in the borough of Manhattan, city, county, and State of New York, have invented a new, original, and ornamental Design for Bust-Covers, of which the following is a specification, reference being had to the accompanying drawing, forming part thereof.

The figure is a perspective view of a bust cover, showing my new design.

I claim:

The ornamental design for a bust cover, as shown.

ALPHONSE MATERA.
